UNITED STATES PATENT OFFICE.

WILLIAM D. POMEROY, OF NORWOOD, OHIO, AND EDWIN C. WRIGHT, OF NEWPORT, KENTUCKY, ASSIGNORS, BY MESNE ASSIGNMENTS, TO THE BULLOCK ELECTRIC COMPANY, A CORPORATION OF OHIO.

CONTROVERSY.

No. 902,834.

Specification of Letters Patent.

Patented Nov. 3, 1908.

Application filed August 4, 1903, Serial No. 168,154. Renewed February 21, 1907. Serial No. 358,726.

To all whom it may concern:

Be it known that we, WILLIAM D. POMEROY and EDWIN C. WRIGHT, citizens of the United States, residing, the former at Norwood, in 5 the county of Hamilton and State of Ohio, and the latter at Newport, in the county of Campbell and State of Kentucky, have invented certain new and useful Improvements in Controllers, of which the following is a full, 10 clear, and exact specification.

Our invention relates to controllers for electric motors and more particularly to controllers adapted to vary the speed of motor by changing the voltage applied thereto and 15 operated from a multiple voltage system.

One object of our invention is to produce a controller which shall be simple in construction, reliable in operation and which will allow convenient access to all parts.

20 Another object is to produce a controller which will have a quick break and so minimize the sparking at contacts.

Another object is to construct a controller which will positively engage each step successively, only one step being taken for each throw of the operating handle, and prevent the drum from stopping between steps.

By our invention movement of the handle subjects a spring to increased tension, which 30 tension is suddenly released, giving a quick turn to the controller cylinder; and we also provide means to quickly and positively check the movement of the controller at the adjacent step. A second throw of the operating handle is then necessary to pass to the 35 following step. By thus providing a quick break we do away with the necessity for providing special devices for blowing out the arc and can also make the parts light and simple 40 in construction and greatly reduce the size of the controller for a given capacity.

Although we have shown and described automatic means for inserting and cutting out a resistance in the armature circuit when 45 change of voltage takes place, this forms no part of our joint invention and we do not claim to be joint inventors of the same. It is shown only for the purpose of a better understanding of our invention.

50 Our invention further consists in the novel construction, combination and arrangement of parts, all as hereinafter described and set forth in the appended claims.

In the accompanying drawings which show

the preferred form of construction,—Figure 55 1 is a diagram showing the development of the controller cylinder and circuits. Fig. 2 is a side view of the controller with the cover removed and some parts in section. Fig. 3 is a detail of the insulating washers. Fig. 60 4 is a plan view of the top plate of the controller. Fig. 5 is a sectional view on the line 5—5 of Fig. 2. Fig. 6 is an enlarged plan view of the arm and pawl carried thereby. Fig. 7 is a side view of the same.

In Fig. 1 the generators are indicated at 1, 1' in series with each other and connected by the switch 2 to the three wire mains 3, 3', 3" and supplying voltages which differ from each other; for example, generator 1 may 70 give 160 volts between mains 3 and 3' and generator 1' may give 90 volts between mains 3' and 3". The armature of the motor whose speed is to be varied is indicated at 4 and its field winding at 5 connected in series with the variable field resistance 6. The field winding and its resistance is connected across the mains 3, 3" by the leads 7, 8 and so receive the full voltage of both generators. In series with the armature lead 9 is the resistance 9^a. Leads to the terminals of switch 10 form a short circuit about the armature resistance when said switch is closed. This switch is provided with an upwardly extending soft iron arm 11, which forms the 80 core of the coil 12. A lower extension from the switch carries the plunger 13 which works in the cylinder 14, forming a dash-pot. The plunger 13 is provided with openings 15 and carries a loosely fitting flat ring 16 which 90 normally closes the openings 15. The cylinder 14 is provided with openings 17 located equally distant from the closed bottom of the cylinder. When current passes in coil 12, the switch is raised with a comparatively 95 slow movement as the air passes to the bottom of the plunger only by leakage about the same. Just before the switch is closed, however, the plunger passes by the holes 17, permitting a free flow of air below it and the 100 switch then closes with a sudden movement. When no current passes in coil 12, the switch quickly falls by gravity or spring pressure, the air from beneath the plunger passing freely through the holes 15 as the ring 16 is 105 then raised from its seat.

The parts above described are interconnected and also connected to the fingers 1^a,

^{1b, 1c, . . . 1e} of the controller as shown. The controller cylinder is made up of three drums 18, 19 and 20 insulated from each other. The two upper drums control the connections to the armature and have the contacts indicated held upon lugs projecting from the body of the drum. The lower cylinder changes the field resistance and is in the form of a cylinder having cut-away portions. 5

10 As the cylinder is revolved from off position the fingers 1^a, 1^b, . . . 1^e take the successive positions indicated by the lines 2^a, 2^b, 2^c, . . . 2^e for forward rotation and the positions 3^a, 3^b, . . . 3^e for backward rotation of the motor. 15

15 For position 2^a the path of the current is as follows: from main 3^a to finger 1^a, contact 21, drum 19, contact 22, finger 1^b, lead 23, armature 4, lead 24, switch 10, which is closed, leads 9 and 25, finger 1^c, contact 26, 20 drum 18, contact 27, finger 1^d to main 3^a, thus subjecting the armature of the motor to the voltage of generator 1'. For position 2^b, the field connections are from the main 3^a through lead 7, field 5, finger 1^e, drum 20, 25 finger 1^a, lead 8 to main 3^a, thus subjecting the field to the full voltage of mains 3, 3^a with all of resistance 6 cut out. Connection is also made from main 3^a through coil 12 to finger 1^a and drum 20, which is connected to 30 main 3^a through finger 1^a, and lead 8. The coil 12 is therefore subjected to the voltage of generator 1' and switch 10 is closed. 35

For position 2^b, finger 1^a, is cut out of contact with drum 20, and a section of resistance 35 6 is inserted in the field circuit, the field current passing from the field winding 5 to finger 1^a through a section of the field resistance and then to drum 20. No other changes take place, and by thus weakening the field 40 of the motor an increased speed is obtained. In the same way for position 2^c a still further weakening of the field takes place by inserting another section of resistance 6 in the field circuit, and in this position current passes 45 from the field 5 through two sections of resistance to finger 1^a and drum 20.

For position 2^d the armature connections are from main 3^a to finger 1^e, contact 28, drum 19, contact 29, finger 1^e, lead 23, armature 4, lead 24, switch 10, leads 9 and 25, finger 1^b, contact 30, drum 18, contact 31, finger 1^c, to main 3^a. The armature of the motor is therefore subjected to the voltage of generator 1 which is greater than that of generator 1'. The field connections and those of coil 12 are the same for this position as for position 2^a, and the speed of the motor is increased by the increase in voltage applied to its armature. For positions 2^e and 2^a the 55 only changes that take place are the weakening of the field by cutting in sections of resistance 6 as in positions 2^b and 2^c.

For position 2^e the armature connections are from main 3^a to finger 1^b, contact 32, 60 drum 19, contact 33, finger 1^c, lead 23, arma-

ture 4, lead 24, switch 10, leads 9 and 25, finger 1^b, contact 34, drum 18, contact 35, finger 1^a, to main 3. The armature of the motor is therefore subjected to the total voltage of both generators. The field connections 70 and those of coil 12 are the same as for positions 2^a and 2^d, with resistance 6 cut out, an increased speed is obtained by the increase in electromotive force applied to the motor armature. 75

For positions 2^b, 2ⁱ, 2^j, 2^k, and 2^l the connections remain the same except that sections of resistance 6 are successively cut in until it is all in circuit and in this manner successively weakening the field for increases in 80 speed from 2^b to 2^l.

It will be noted that in passing from position 2^c to 2^d, and from 2^d to 2^e, at which times the change in voltage applied to the motor armature takes place, finger 1^e is momentarily cut out of contact with the drum 20 and circuit through coil 12 is broken. At the instant finger 1^e breaks contact with drum 20, switch 10 drops and resistance 9^a is inserted in series with the armature 4, so that 90 when the increased voltage is applied to the armature, this resistance will prevent a too sudden rush of current with consequent strains on the motor. As coil 12 is again placed in circuit at positions 2^d and 2^e, the 95 switch 10 will be closed and the resistance 9^a short circuited, but on account of the slow upward movement of the switch the motor will have had sufficient time to increase in speed before the switch is closed. In 100 starting the switch 10 is closed in the same manner.

For reverse rotation of the motor, the fingers are in position 3^a to 3^e successively. For position 3^a the current passes from main 3^a to finger 1^a, contact 36, drum 19, contact 37, finger 1^b, lead 9, switch 10, lead 24, armature 4, leads 23 and 38, finger 1^c, contact 39, drum 18, contact 40, finger 1^d, to main 3^a. The armature 4 is therefore subjected to voltage of generator 1', and the armature current is reversed, while the field is the same as for position 2^a. The direction of rotation of the motor is therefore reversed and the motor operates at its slowest speed. For positions 3^b and 3^c the field strength is weakened as before. For position 3^b the circuit is as follows: main 3^a, finger 1^a, contact 41, drum 19, contact 42, finger 1^b, lead 9, switch 10, lead 24, armature 4, leads 23 and 38, finger 1^c, contact 43, drum 18, contact 44, finger 1^d to main 3^a. For this position, although the motor has its full field strength as in position 3^a, an increased speed is obtained by reason of the armature being subjected to the voltage of generator 1. At positions 3^d and 3^e, increased speeds are obtained by weakening the field strength. For position 3^e the connections are as follows: from main 3^a to finger 1^a, contact 45, drum 19, contact 46, fin- 125 ger 1^b, contact 47, drum 18, contact 48, finger 1^c, contact 49, drum 17, contact 50, finger 1^d to main 3^a. 130

ger 1^a, lead 9, switch 10, lead 24, armature 4, leads 23 and 38, finger 1^c, contact 47, drum 18, contact 48, finger 1^a to main 3, the motor in this case being subjected to the total voltage of both generators. At positions 3^b and 3^c the field strength is weakened. In passing from positions 3^c to 3^d and from 3^d to 3^e, the armature resistance 9^a is cut in to relieve the strain on the motor, as already explained 10 with reference to passing from positions 2^c to 2^d and from 2^d to 2^e.

It is therefore evident from the above description that by use of a single drum, which controls both the field and armature connections, we obtain twelve speeds forward and 15 nine in a reverse direction.

The mechanical construction of the controller is illustrated in Figs. 2 to 7. The controller frame consists of the back plate 49, 20 having the perforated lugs 50 for securing to a suitable support, and arms 51, extending from each corner, to which are secured by the bolts 52 the top plate 53 and the base 54. In order to exactly center these parts with reference to each other, dowel pins 55 are passed through each arm 51 and top and bottom plates. A suitable cover is adapted to enclose all parts and engage the rims 56 and 57 on the top and bottom plates. The controller shaft 58 is journaled in the hub 59 of the top plate and the boss 60 on the lower plate. The three drums 18, 19 and 20 are preferably of brass and are insulated from the shaft by a sleeve 61 of insulating material. Each drum is provided with an end plate 62, recessed to receive the keys 63 formed on the insulating washers 64. All parts are clamped together and connected to the shaft by end clamps 65 which engage the keys 63 of the end washers 64, and are connected to the shaft by the pins 66. The contacts carried by drums 18 and 19 are supported on lugs 67 integral with the drums and secured to said lugs by screws 68. The drum 20 is cast in one piece and consists of an outer cylinder of the configuration shown in Fig. 1, connected to its inner supporting cylinder 69 by ribs 70.

Fingers 1^a, 1^b, . . . 1^e are secured by screws 50 71 to metallic strips 72, which have integral therewith the connectors 73. The strips 72 are mounted on an insulating support 74, made of maple soaked in paraffin which is bolted to the back plate 49. The conducting strips 72 are attached to their support by bolts 75. Openings 76 and 77 are provided in the back plate 49 and base plate 54 for bringing in connecting leads. Each conducting strip 72, which carries fingers engaging contacts on drums 18 and 19 is provided with a fan shaped extension 78, and a screw 79, having the lock nut 80, passes through each finger and engages by end contact the extension 78. As the fingers are 60 made of spring brass, adjustment of the

screws 79 will regulate the position and amount of pressure of the fingers upon the contacts.

In order to confine and limit the spaces in which arcing takes place, and so tend to smother the arc and prevent arcing across from one contact to the next, we provide the deflectors 81. These are made of sheets of insulating material about $\frac{1}{8}$ " thick, and in general outline form a triangle. One is 75 placed between each set of contacts on drums 18 and 19 so that the arc is formed at about the center of the deflector. From the top and bottom plates extend the lugs 82^a to which the metal strips 82, 82 are secured by the bolts 82^b. The two rods 83, 83 pass through the deflectors and the strips 82, 82, and the deflectors are spaced from each other and from the strips 82 by the fiber sleeves 84 on the rods. The nuts 83^a on the ends of the rods firmly clamp all parts together. The triangular deflectors are supported from a third point by the above mentioned extensions 78 which project between them. To remove the deflectors, it is simply necessary 80 to unscrew the bolts 82^b and the rods and deflectors may be removed as a whole, thus giving convenient access to the fingers and contacts.

The operating mechanism will now be described. The shaft 58 extends through the top plate and fixed thereto is the arm 85, bearing the pawl 86, pivoted between the extensions 87, 87. The pawl carries the steel plate 88 riveted between the side pieces 89. 100 The plate 88 engages the notches 90, formed in a rim 91 on the top plate 53. The pawl has a lower extension 92 to which one end of a spring 93 is attached, the other end being attached to a lug 94 formed within the shell 105 of the arm 85. The pawl is also provided with an upward extension 95 to which a steel roller 96 is secured by the screw 97. This roller is cylindrical in form and provided with the head 96^a. A lug 98 extends downwardly from the arm 85 and is adapted to engage the stop 99 on the top plate. The operating handle 100 is loosely mounted upon the shaft 58, and a spring 101 with the projecting ends 102, encircles the hub 103 of the handle. A projection 104 extends downwardly from the under side of the handle and is parallel to a similar projection 105, extending upwardly from the arm 85. These projections are provided with notches 106 110 on opposite sides in which lay the ends 102 of the spring. The side pieces 108 of the handle carry the cylindrical rollers 107, secured thereto by the screws 110. The arm 85 is provided with the upwardly extending lugs 111 adapted to be engaged by the projection 104 from the handle.

In the operation of the device, turning the handle carries along with it by means of the projection 104 one or the other of the ends 130

102 of the spring, depending upon the direction in which the handle is turned, and, as the arm 85 remains stationary, the tension of spring 101 is greatly increased. One of the rollers 107 then engages the bead 96 on the outer side, which action forces the lug 95 inward and raises the pawl 88 from its engaging notch. The tension of the spring 101 then quickly turns the cylinder, giving 10 a quick-break between the fingers and contacts of the drums, and the spring 93 checks this movement by forcing the pawl into the adjacent notch. A second turn of the handle is then necessary to bring the rollers 107 15 into engagement with the roller 96 in order to pass to the following notch and obtain a further change of speed. Owing to the quick-break and to the further fact that the circuit, upon change of voltage, is broken at 20 four points, as is evident from Fig. 1, the sparking is reduced to a minimum, and the sparking that does occur is confined and limited to a small area by the deflectors. The connections and circuits by which 25 change of speed is obtained, as well as the automatic control of the armature resistance, has already been explained. After passing from the off position to the positions 2¹ or 3, further movement is prevented by the lug 88 30 on the arm 85 coming into contact with the stop 99; and in these positions undue strain upon spring 101 and damage to other parts is prevented by the projection 104 engaging one or the other of the lugs 111.

55 I claim as my invention:—

1. The combination of a controller cylinder, contacts carried thereby, deflectors between the contacts, rods for supporting the deflectors, each rod passing through all the deflectors, and projections secured to the frame of the controller, located between adjacent deflectors.

2. The combination of a controller cylinder, contacts carried thereby, deflectors between the contacts, rods for supporting the deflectors, each rod passing through all the deflectors, and projections secured to the frame of the controller located between adjacent deflectors, the rods and deflectors being 50 removable as a whole.

3. The combination of a controller cylinder, contacts carried thereby, deflectors between the contacts, rods passing through the deflectors, said deflectors being spaced by sleeves of insulating material on said rods, and projections secured to the frame of the controller located between adjacent deflectors.

4. The combination of a controller cylinder, contacts carried thereby, deflectors between the contacts, rods passing through the deflectors, said deflectors being spaced by sleeves of insulating material on said rods, and projections secured to the frame of the controller located between adjacent deflectors.

tors, the rods and deflectors being removable as a whole.

5. The combination of a controller cylinder, contacts carried thereby, fingers engaging the contacts and connected to conducting strips, deflectors between said contacts, rods passing through the deflectors, said deflectors being spaced by sleeves of insulating material on said rods, and an extension from each of said conducting strips for supporting and spacing the deflectors, the rods and deflectors being removable as a whole.

6. In an operating device for a controlling switch, the combination of a member controlling the movement of the movable switch contact or contacts, a primary member, a notched controller plate, a spring engaging said members and located above said notched plate, a catch carried by said controlling member and adapted to engage openings in the controller plate, and means carried by said primary member acting to withdraw said catch.

7. In an operating device for a controlling switch, the combination of a member controlling the movement of the movable switch contact or contacts, a primary member, a notched controller plate, resilient means located above said plate tending to keep said members in fixed positions relatively to each other, a catch carried by said controlling member and adapted to engage openings in the controller plate, and means carried by said primary member acting to withdraw said catch upon moving said primary member.

8. In an operating device for a controlling switch, the combination of a member controlling the movement of the movable switch contact or contacts, a primary member, a notched controller plate resilient means located above said plate tending to keep said members in fixed positions relatively to each other, a catch carried by said controlling member and adapted to engage openings in the controller plate, and means carried by said primary member acting to simultaneously increase the tension of said resilient means and to withdraw said catch upon moving said primary member.

9. In an operating device for a controller, the combination of an arm fixed to the controller shaft, a handle, a spring engaging said arm and handle, a pawl carried by said arm and adapted to engage notches in the controller plate, and means carried by the handle acting to withdraw the pawl upon turning the handle.

10. In an operating device for a controller, the combination of an arm fixed to the controller shaft, a handle, a spring tending to keep said arm and handle in fixed positions relatively to each other, a pawl carried by said arm and adapted to engage notches in the controller plate, and means carried by the handle acting to withdraw the pawl upon turning the handle.

the handle acting to withdraw the pawl upon turning the handle.

11. In an operating device for a controller, the combination of an arm fixed to the controller shaft, a handle, a spring tending to keep said arm and handle in fixed positions relatively to each other, a pawl carried by said arm and adapted to engage notches in the controller plate, and means carried by the handle acting to simultaneously increase the tension of said spring and to withdraw the pawl upon turning the handle.

12. In an operating device for a controller, the combination of an arm secured to the controller shaft, a pawl carried thereby adapted to engage notches in the controller plate, a spring for forcing said pawl into said notches, an operating handle and a spring to keep said handle in line with said arm, said handle acting to withdraw the pawl from the notch engaged upon turning the handle.

13. In an operating device for a controller, the combination of an arm fixed to the controller shaft, a handle, a spring tending to keep said arm and said handle in fixed positions relatively to each other, a pawl carried by said arm and adapted to engage the notched controller plate, a spring attached to said pawl and arm, and projecting parts carried by the handle acting to engage the pawl upon turning the handle.

14. In an operating device for a controller, the combination of an arm fixed to the controller shaft, a handle, a spring tending to keep said arm and said handle in fixed positions relatively to each other, a pawl carried by said arm and adapted to engage the notched controller plate, a spring attached to said pawl and arm, and rollers carried by the handle acting to engage the pawl upon turning the handle.

15. In an operating device for a controller, the combination of an arm fixed to the controller shaft, a handle, a spring tending to keep said arm and said handle in fixed positions relatively to each other, a pawl carried by said arm, said pawl having a projecting part and adapted to engage the notched controller plate, a spring attached to said pawl and arm, and projecting parts carried by the handle acting to engage said projecting part on the pawl upon turning the handle.

16. In an operating device for a controller, the combination of an arm fixed to the controller shaft, a handle, a spring tending to keep said arm and said handle in fixed positions relatively to each other, a pawl carried by said arm, said pawl having a projecting part and adapted to engage the notched controller plate, a spring attached to said pawl and arm, and rollers carried by the handle acting to engage said projecting part on the pawl upon turning the handle.

17. In an operating device for a controller, the combination of an arm fixed to the controller shaft, a handle, a spring tending to keep said arm and said handle in fixed positions relatively to each other, a pawl carried by said arm and adapted to engage the notched controller plate, a spring attached to said pawl and arm, and rollers carried by the handle acting to engage said projecting part on the pawl upon turning the handle.

troller shaft, a handle, a spring tending to keep said arm and said handle in fixed positions relatively to each other, a pawl carried by said arm and adapted to engage the notched controller plate, a roller carried by said pawl, a spring attached to said pawl and arm, and projecting parts carried by the handle acting to engage said roller upon turning the handle.

18. In an operating device for a controller, the combination of an arm fixed to the controller shaft, a handle, a spring tending to keep said arm and said handle in fixed positions relatively to each other, a pawl carried by said arm and adapted to engage the notched controller plate, a roller carried by said pawl, a spring attached to said pawl and arm, and rollers carried by the handle acting to engage said roller upon turning the handle.

19. In an operating device for a controller, the combination of an arm fixed to the controller shaft, a handle, a spring tending to keep said arm and said handle in fixed positions relatively to each other, a pawl pivoted between extensions on said arm and adapted to engage the notched controller plate, a spring attached to said pawl and arm, a roller carried by an upward extension on said pawl, rollers carried by said handle and extending downwardly acting to engage the roller carried by the pawl upon turning the handle.

20. The combination of multiple voltage mains, a motor, a field resistance for said motor, a controller and connecting leads, said controller having a single cylinder and contacts thereon, arranged so that turning the cylinder in one direction for forward speeds varies the voltage supplied to the armature circuit of the motor and varies the field resistance, and turning the cylinder in the opposite direction varies the voltage supplied to the armature circuit of the motor, and also reverses the rotation of the motor.

21. The combination of multiple voltage mains, a motor, a field resistance for said motor, a controller and connecting leads, said controller having a single cylinder and contacts thereon, arranged so that turning the cylinder in one direction for forward speeds varies the voltage supplied to the armature circuit of the motor and varies the field resistance, and turning the cylinder in the opposite direction varies the voltage supplied to the armature circuit of the motor, and varies the field resistance and also reverses the rotation of the motor.

22. In a controlling switch, the combination of the movable switch element, a fixed member, a catch carried by said element for locking the same in definite positions to said fixed member, a second element movable with reference to said first named element, and means located above said fixed member and controlled by said second element for

exerting a force upon said first element tending to move the same and for releasing said catch.

23. In a controlling switch, the combination of a pivoted arm for controlling the movement of the movable switch contact or contacts, a fixed member, a catch carried by said arm and adapted to lock the same in definite positions to said fixed member, a second arm movable with reference to said first named arm and normally in alinement therewith, resilient means connecting said arms and located above said fixed member, and means carried by said second arm for releasing said catch after said second arm has been moved a predetermined amount with reference to said first named arm.

24. In a controlling switch, the combination of a pivoted arm for controlling the movement of the movable switch contact or

contacts, a fixed member, a catch carried by said arm and adapted to engage openings for locking the arm in definite positions to said fixed member, a second arm pivoted concentrically with reference to said first named arm, movable with reference thereto and normally parallel therewith, a spring connecting said arms and located above said fixed member, and means carried by said second arm and adapted to displace said catch after said second arm has been moved a predetermined amount with reference to said first named arm. 25 30

In testimony whereof we affix our signatures, in presence of two witnesses.

exerting a force upon said first element tending to move the same and for releasing said catch.

23. In a controlling switch, the combination of a pivoted arm for controlling the movement of the movable switch contact or contacts, a fixed member, a catch carried by said arm and adapted to lock the same in definite positions to said fixed member, a second arm movable with reference to said first named arm and normally in alinement therewith, resilient means connecting said arms and located above said fixed member, and means carried by said second arm for releasing said catch after said second arm has been moved a predetermined amount with reference to said first named arm.

24. In a controlling switch, the combination of a pivoted arm for controlling the movement of the movable switch contact or

contacts, a fixed member, a catch carried by said arm and adapted to engage openings for locking the arm in definite positions to said fixed member, a second arm pivoted concentrically with reference to said first named arm, movable with reference thereto and normally parallel therewith, a spring connecting said arms and located above said fixed member, and means carried by said second arm and adapted to displace said catch after said second arm has been moved a predetermined amount with reference to said first named arm. 25 30
